CLAIM

The ornamental design for a garden umbrella with telescoping stand, as shown and described.

DESCRIPTION

FIG. 1 is a perspective view of a garden umbrella with telescoping stand showing my new design;

FIG. 2 is a top plan view thereof;

FIG. 3 is a right side elevational view thereof;

FIG. 4 is a front elevational view thereof;

FIG. 5 is a left side elevational view thereof;

FIG. 6 is a rear elevational view thereof;

FIG. 7 is a bottom plan view thereof;

FIG. 8 is a right side elevational view in a retracted and closed position;

FIG. 9 is a right side elevational view in an extended and closed position;

FIG. 10 is a perspective view in a retracted and open position; and,

FIG. 11 is a perspective view in an extended and open position.

The broken line showing of environment in FIG. 1 is for illustrative purposes only and forms no part of the claimed design.
